UNITED STATES PATENT OFFICE.

HAROLD M. WHITING, OF ROCKY POINT, NEW YORK.

SWITCH-CONTROL DEVICE.

Application filed March 19, 1924. Serial No. 700,441.

To all whom it may concern:

Be it known that I, HAROLD M. WHITING, a citizen of the United States, and resident of Rocky Point, in the county of Suffolk and State of New York, have invented a new and useful Improvement in Switch- Control Devices, of which the following is a specification.

Where manually operated railway switch- 10 es are employed, many accidents have been caused by the switch operator unintentional- ly leaving the switches open.

The object of my invention is to provide 15 means for preventing this unintentional- leaving of the switch open, said means in- cluding an enclosure for the switch operator as, for instance, a cage within which the switch operating lever is located, said cage having a normally open door for the entrance 20 and exit of the switch operator; and coating devices so constructed, arranged and operated that the switch operator must enter the cage, close the door and lock himself in before he 25 can move the switch lever from its "closed" position to its "open" position; and the switch operator must first move the switch lever back from its "open" position to its "closed" position before he can unlock the 30 door to open it, to leave the cage.

A practical embodiment of my invention is represented in the accompanying draw- ings, in which—

Fig. 1 represents a front elevation with 35 the switch lever in its "closed" position and the cage door open and locked to the switch lever.

Fig. 2 represents a horizontal section taken in the plane of the line II—II of Fig. 1 with the parts in the positions shown 40 in Fig. 1.

Fig. 3 represents a similar section with 45 the parts in the positions they assume when the cage door has been closed and locked and the switch lever moved from its "closed" position to its "open" position.

Fig. 4 represents a detail section taken in the plane of the line IV—IV of Fig. 1.

The horizontally arranged switch lever 1 is secured to the upright bar 2, which bar 50 is provided with the usual arm 3 and connection 4, leading to the railway switch (not shown herein).

An enclosure of sufficient size to accom- 55 modate the switch operator is provided,

which enclosure is herein shown as a cage 55 enclosing the switch lever 1, which cage has a flat vertical back wall 5, a semi-circular vertical front wall 6 and a suitable roof 7. The semi-circular front wall 6 of the cage is provided with a door 8 which is held normally open by a suitable spring 9, for instance. A bracket 10 projecting from an upright 11 within the cage may be provided with a latch 12 for yieldingly holding the switch lever 1 in its "closed" position. 60

The normally open door 8 is secured to the normally closed switch lever as, for instance, by a padlock 13.

The means which I have shown for lock- 70 ing the cage door closed and permitting the switch lever to be moved to its "open" position after the switch operator has entered the cage is constructed, arranged and oper- ated as follows:

The inner member 14 of a hinged arm is 75 hinged at 15 to the bracket 10 to swing from a vertical position to a horizontal position and when in its horizontal position the outer end of the said inner member 14 bears against the back of the outer edge 80 of the door 8, when the door is closed. An outer member 16 of this hinged arm is hinged at 17 to the outer end of the inner member 14, to swing laterally with respect thereto, the outer end of which member 16, 85 when the arm is in its horizontal position, rests upon a bracket 18 projecting from an upright 19. The lower end of the pin 20 in the free end of the outer member 16 of the hinged arm is arranged to enter a hole 90 21 in the bracket 18, and the upper end of the said pin projects upwardly when the hinged arm is in its horizontal position, sufficient to overlap the switch lever 1 when it is moved to its "open" position shown in 95 Fig. 3.

A latch 22 is hinged to the upright 11 in position to hold the hinged arm in its vertical position when the switch lever is moved to its "closed" position.

It will thus be seen that when it is de- 100 sired to open the switch, the switch operator will have to enter the cage and unlock the open door from its engagement with the switch lever. The swinging arm is then 105 released from the latch 22 and swung down into its horizontal position and the outer member 16 unfolded and brought into locked

engagement with the bracket 18, thus locking the door 8 closed with the switch operator inside the cage. The switch operator may then move the switch lever 1 from its "closed" position shown in Fig. 2, to its "open" position shown in Fig. 3. It will be seen that the switch operator is locked in the cage until he first moves the switch lever from its "open" position to its "closed" position, permitting him to release the outer member 16 of the hinged arm and fold it against the inner member 14 and then swing the two members upwardly into their vertical position where they may be so held by the latch 22. This manipulation of the parts will permit the door 8 to swing open and allow the switch operator to leave the cage.

It is evident that various changes may be resorted to in the construction, form and arrangement of the several parts without departing from the spirit and scope of my invention; hence, I do not wish to limit myself to the particular embodiment herein shown and described, but

25. What I claim is:

1. A manually operated switch lever, an enclosure therefor having a door, a lock for securing the door to the switch lever when the door is open and the lever is in its "closed" position, and means requiring the opening of the lock and closing of the door to permit the moving of the switch lever to its "open" position.

2. A manually operated switch lever, an enclosure therefor having a door, a lock for securing the door to the switch lever when the door is open and the lever is in its "closed" position, and means requiring the opening of the lock and closing of the door to permit the moving of the switch lever to its "open" position and requiring the moving of the switch lever to its "closed" position to permit the opening of the door.

3. A manually operated switch lever, an enclosure therefor having a door, and means requiring the closing of the door to permit the moving of the switch lever to its "open" position, said means comprising a hinged arm arranged when in one position to prevent the door from being opened and when in its other position to permit the door to be opened, said hinged arm comprising two members hinged together.

4. A manually operated switch lever, an enclosure therefor having a door, and means requiring the closing of the door to permit the moving of the switch lever to its "open" position, said means comprising a hinged arm arranged when in one position to prevent the door from being opened and when in its other position to permit the door to be opened, said hinged arm comprising two members hinged together, one member being arranged to swing laterally and the other member vertically.

5. A manually operated switch lever, an enclosure therefor having a door, means requiring the closing of the door to permit the moving of the switch lever to its "open" position, said means comprising a hinged arm arranged when in one position to prevent the door from being opened and when in its other position to permit the door to be opened, said hinged arm comprising two members hinged together, one member being arranged to swing laterally and the other member vertically, and a latch for removably holding the hinged arm in its vertical position.

6. A manually operated switch lever, a cage enclosing the same, said cage having a door, a lock for securing the door to the switch lever when the door is open and the lever is in its "closed" position, and means requiring the opening of the lock and closing of the door to permit the moving of the switch lever to its "open" position.

7. A manually operated switch lever, a cage enclosing the same, said cage having a door, a lock for securing the door to the switch lever when the door is open and the lever is in its "closed" position, and means requiring the opening of the lock and closing of the door to permit the moving of the switch lever to its "open" position and requiring the moving of the switch lever to its "closed" position to permit the opening of the door.

8. A manually operated switch lever, a cage enclosing the same, said cage having a door, and means requiring the closing of the door to permit the moving of the switch lever to its open position, said means comprising a hinged arm arranged when in one position to prevent the door from being opened and when in its other position to permit the door to be opened, said hinged arm comprising two members hinged together.

9. A manually operated switch lever, a cage enclosing the same, said cage having a door, and means requiring the closing of the door to permit the moving of the switch lever to its "open" position, said means comprising a hinged arm arranged when in one position to prevent the door from being opened and when in its other position to permit the door to be opened, said hinged arm comprising two members hinged together, one member being arranged to swing laterally and the other member vertically.

10. A manually operated switch lever, a cage enclosing the same, said cage having a door, means requiring the closing of the door to permit the moving of the switch lever to its "open" position, said means comprising a hinged arm arranged when in one position to prevent the door from being opened and when in its other position to permit the door to be opened, said hinged arm

comprising two members hinged together, one member being arranged to swing laterally and the other member vertically, and a latch for removably holding the hinged arm in its vertical position.

11. A manually operated switch lever, a cage enclosing the same, said cage having

a normally open door, and means for locking the open door to the switch lever when the lever is in its "closed" position.

In testimony, that I claim the foregoing as my invention, I have signed my name this 13th day of March, 1924.

HAROLD M. WHITING.
